FIG. 1.

FIG. 2.

FIG. 3.

FIG. 4.

FIG. 5.

FIG. 6.

INVENTOR
PIERRE BASMAISON
by White Prost Evans
HIS ATTORNEYS.

UNITED STATES PATENT OFFICE.

PIERRE BASMAISON, OF SAN FRANCISCO, CALIFORNIA.

BIT.

Application filed December 15, 1923. Serial No. 680,892.

My invention relates to bits for wood-working tools and machines, such as bench planes, spoke shaves, chisels, jointers, surfacers and the like; and one of the objects 5 of the invention is to provide a bit having a replaceable cutter such that perfect setting and alignment of the cutter in the bit follows the assembling of the parts as a matter of mechanical certainty instead of as a matter 10 of skillful handling.

Another object is to provide a bit adapted to employ a thin cutter that may be replaced when dull as readily as blades are replaced in a safety razor.

15 Another object is to provide a bit having a replaceable cutter formed with a double bevel cutting edge, and having its cutter end so shaped that the lateral faces of the bit adjacent the cutter lie in planes coincident 20 with the bevels thereof, thus insuring correct sharpening of the cutter while positioned in the bit, if desired.

My invention possesses other objects and 25 features of advantage, some of which, with the foregoing, will be set forth in the following description of the preferred form of my invention which is illustrated in the drawings accompanying and forming part of the specification. It is to be understood that 30 I do not limit myself to the showing made by the said drawings and description, as I may adopt variations of the preferred form within the scope of my invention as set forth in the claims.

35 Referring to the drawings:—

Figure 1 is a central vertical section thru one of my bits assembled in a low angle block plane.

Figure 2 is a side elevation of my bit.

40 Figure 3 is a plan view of the under side of the bit.

Figure 4 is a side view of a chisel showing a modified embodiment of my invention.

45 Figure 5 is an end view of a jointer head showing another adaption of my invention.

Figure 6 is a side view of the spring employed in the adaption of my invention illustrated in Figure 5.

50 The bit of my invention comprises a cutter blade 2 formed with the usual slot 3 extending longitudinally therethru along a median line and also provided with the usual transverse notches 4 on its bottom lateral face adjacent one end. The opposite upper lateral 55 face of the cutter blade is formed with a

rabbet 6 having a shoulder 7, to provide a recess for the reception of a cutter 8 having a rear non-cutting edge 9 complementary to the shoulder 7 of the rabbet. The rabbet is formed in the beveled end of the blade which 60 forms an angle of approximately $12\frac{1}{2}^{\circ}$ to the bottom lateral face, and the cutting edge of the cutter 8 is formed by the intersection of the planes of the bevels 11, the plane of each bevel forming an angle of 65 approximately $12\frac{1}{2}^{\circ}$ with the median longitudinal plane of the cutter.

Overlying the cutter blade and secured thereto at the end opposite the cutter by rivets 12, is a clamp plate 13 adapted to be 70 pressed into clamping contact with the cutter 8, and provided with a slot 14 in register with the slot 3 of the cutter blade. The end 16 of the clamp plate adjacent the cutter is curved downwardly to form a clamping 75 edge 17 and the upper face of the plate 13 contiguous to the clamping edge is beveled, so that when the clamp plate is depressed the face of the bevel and the upper bevel 11 of the cutter lie in the same plane. In order to 80 prevent chips from passing between the cutter and the bit I prefer to form a second short but steep bevel immediately adjacent the clamping edge 17 of the clamp plate 13 which forces the chips up and away from the 85 point of contact of the clamp plate and the cutter, and the sharp edge of the cutter blade 2 is also similarly relieved to avoid a weak thin edge under the cutter.

Means are provided for resiliently retaining the cutter in position in the cutter blade when not secured by the clamp plate. This is accomplished by a plate spring 18 suitably secured to the upper lateral face of the cutter blade and so arranged that the 90 free end of the spring engages the cutter with sufficient force to retain it in place, but not sufficient to prevent its ready removal. The free end of the spring overlies the cutter at the point of contact of the 95 edge 17 of the clamp plate 13 so that when the plate is depressed the spring is held flat.

100 The bit disclosed in Figures 2 and 3 is adapted for use in a low angle block plane of a well-known make as illustrated in Figure 1, hence it is unnecessary to describe the mechanism of the plane in detail.

105 The bit is positioned in the plane bottom in the usual manner by the lever cap screw 110 19 passing thru the slots in the clamp lever

and the cutter blade, and the clamp plate is depressed to clamp the cutter by the lever cap 20.

It is understood of course that the cutter 6 is resiliently retained by the spring 18, in the cutter blade during the assembling of the cutter blade in the plane.

Longitudinal adjustment of the bit in the plane is effected in the usual manner by the 10 frog 21, which engages the notches 4 in the cutter blade.

It will be noted that since the bottom bevel 11 of the cutter and the bottom lateral face of the cutter blade 2 lie in co-incident 15 longitudinal planes, the bit may be positioned in the plane in the same manner as the old style bit. If desired the cutter may be whetted by removing the bit as a unit from the plane and holding the clamp plate 20 in depressed position with the hand or a bolt during the operation. The bevels of the clamp plate and cutter blade will insure correct positioning of the bit on the stone.

In the modification of my invention disclosed in Figure 4 the bit is in the form of a chisel comprising a body portion 25 which is tapered at one end and rabbeted to receive the cutter 26. A resilient clamp plate 27 is suitably secured to the body portion and 30 its tapered free end 28 is held in clamping engagement with the cutter 26 by countersunk screws 29 which are threaded into the body portion adjacent the cutter. The cutter is formed with double bevels 31 and 35 angularly disposed in the rabbet formed in the body portion so that its bottom bevel lies in a plane co-incident with the bottom face of the chisel. The tapered end 28 of the clamp plate 27 similarly lies in a plane 40 co-incident with the top bevel of the cutter.

Figure 5 illustrates the adaption of my invention to a safety jointer head wherein the bit comprises a cutter blade 33 having a tapered end 34 provided with a rabbet 36.

The cutter 37 disposed in the rabbet is in 45 this instance formed with a single bevel cutting edge 38 lying in a plane co-incident with the tapered end of the cutter blade 33.

The clamp plate 39 comprises a throat piece which is held in tight engagement with the cutter 37 and secured in the head by a plurality of key plugs 41 wedged in tapered sockets 42 by the hollow set screws 43. A channel 44 formed in the face of the throat piece 39 adjacent the cutter blade 55 insures clamping contact of its forward end 45 with the cutter and provides a passage between the throat piece and the cutter blade for the reception of a corrugated plate spring 46 adapted to separate these 60 last named elements when the key plugs are loosened thus facilitating the removal of the cutter.

I claim:—

1. A bit comprising a cutter blade having a rabbeted edge, a loose replaceable cutter adapted to seat in said rabbet and comprising a thin narrow flat smooth strip, and a clamp plate adapted to bear against said cutter blade and cutter to rigidly secure the 70 cutter in the cutter blade.

2. A bit comprising a cutter blade having a rabbet formed in the end thereof, a detached cutter arranged in said rabbet, resilient means for retaining said cutter in the 75 rabbet, and a clamp plate adapted to rigidly secure the cutter in the rabbet.

3. A plane bit comprising a cutter blade having a rabbet formed in the end thereof, a cutter arranged in said rabbet, resilient means for retaining said cutter in said rabbet, and a resilient clamp plate normally free of said cutter and adapted to be pressed into clamping contact with the cutter by the wedge of the plane.

In testimony whereof, I have hereunto set my hand.

PIERRE BASMAISON.
